UNITED STATES PATENT OFFICE.

EUGENE F. MEADOR, OF DANVILLE, VIRGINIA.

ILLUMINATING APPARATUS.

1,205,916.

Specification of Letters Patent. Patented Nov. 21, 1916.

Application filed May 3, 1915. Serial No. 25,563.

To all whom it may concern:

Be it known that I, EUGENE F. MEADOR, a citizen of the United States, residing at Danville, in the county of Pittsylvania and State of Virginia, have invented certain new and useful Improvements in Illuminating Apparatus, of which the following is a specification.

This invention relates to improvements in illuminating apparatus and more particularly to headlight structures for vehicles, such as automobiles, motor boats, and the like.

The primary object in view is the obtaining of maximum efficiency in the projection of light rays while providing a relatively confined area for the projector.

A further object in view is the taking advantage of the reduced area required for such a projector for providing a supplemental projector assembled in a single headlight casing.

With these and further objects in view, the invention comprises substantially one-half of a parabolic reflector and a concaved reflector disposed to deflect light rays across the line of the axis of the parabola, the reflectors being adapted to contain a light disposed substantially coaxial with the parabola.

The invention further comprises substantially one-half of a parabolic reflector and a substantially semi-globular concaved reflector disposed to reflect light into the first mentioned reflector, and a supplemental reflector disposed adjacent the first mentioned reflector.

The invention still further comprises a headlight casing, a reflector arranged in the lower portion of the casing, a supplemental reflector of proportions reduced relative to the first mentioned reflector and arranged between the first mentioned reflector and the upper portion of the casing, independent lights for the reflectors, the casing being formed at its rear portion with a light exit and the second mentioned reflector being formed at its rear portion with a light exit.

The invention also comprises certain other novel constructions, combinations and arrangements of parts as will be hereinafter specified and claimed.

In the accompanying drawings, Figure 1 is a vertical central section through a

light embodying the features of the present invention, parts being seen in elevation. Fig. 2 is a front elevation thereof.

Referring to the drawing by numerals, 1 indicates a headlight casing preferably of the well known "bullet" shape, to the front of which is detachably connected the door 2 carrying the lens or transparent plate 3. The rear portion of the casing 1 is formed with a light opening 4 closed by a glass cover 5.

Arranged in the lower portion of the casing 1 is the reflector 6 which is formed in the shape of substantially the lower half of a parabolic reflector. The upper edges 70 of the forward portion of the reflector 6 are connected by a flat reflector plate 7. Plate 7 at its inner portion terminates in a substantially semi-globular concave reflector 8 disposed to direct light rays down 75 against the parabolic reflector 6 across the axis of the parabola.

Within the area provided by the rear portion of reflector 6 and by reflector 8 is arranged the incandescent electric light bulb 80 9 having the usual shank 10 detachably interlocked in a socket 11 sustained in the sleeve 12 fixed to the rear of the reflectors 6 and 8, the reflectors being apertured for the passage of the socket 11. Current is 85 supplied to the light 9 through socket 11 by conductors 13 leading from any appropriate source not illustrated, through a sleeve 14 fixed in casing 1. The significance of the structural features of this reflector 90 body whereby the efficient result is secured will now be briefly noted.

As hereinbefore premised, the supplemental reflector 8 is of relatively small area and its focal center is coincident with the 95 focal center of the main reflector 6, at which focal center the source of light is also located. The axis of said reflector 8, as the device is illustrated in the official drawings, leans forwardly from the vertical so as to 100 reflect the light rays striking its surface back through the focal center so as to concentrate these rays as much as possible in the small portion of the reflector 6 onto which they are directed and from which 105 they are reflected forwardly in horizontal planes. The exact angularity of the axis of the supplemental reflector with relation to the axis of the main reflector may vary 110 according to the variation in the height of

lamps from the ground as applied to vehicles of different types or sizes. Advantage is taken of the inefficient point of the reflector device, defined by the juncture of 5 the supplemental and main reflectors, in that at this location the light socket 12 is positioned, and furthermore it is to be observed that the concave reflector 8 is very closely arranged to the light so as to catch 10 the light rays in their most condensed stage and before they have had a chance to diverge, thereby preventing the escape of such rays as might under other conditions pass the flat reflector 7, defeating the object of 15 elimination of the glare.

It will be quite obvious that a very effective concentration of the light by the triple reflector elements arranged in the particular association described hereinbefore is obtained and it therefore becomes feasible to 20 use a low candle power light for the apparatus but yet secure a most desirable reflection while saving a considerable amount of current which would be required for a high 25 candle power light most usually employed.

The upper portion of the casing 1 is occupied by a reflector 15 of reduced size relative to reflector 6. The reflector 15 has its upper portion forming substantially one-half of a 30 parabolic reflector, and the lower portion of the reflector, while curved rearwardly as clearly seen in Fig. 1, is substantially straight transversely as clearly seen in Fig. 2. A light 16 of similar structure and arrangement to light 9 but of smaller caliber is arranged in the apex of reflector 15 and supplied with current through conductors 18 leading through sleeve 14 from any appropriate source of current. The lower portion 35 of reflector 15 is apertured at 19, the aperture being closed by a transparent plate 20 preferably of glass. The aperture 19 is located relative to aperture 4 such that light rays passing through aperture 19 will be 40 projected through aperture 4 and thus light the structure in the rear, as for example the side or running board of the car, or side of 45 a boat.

It will be noted that the reflector 15 is so 50 arranged and constructed as to project the light rays ordinarily above the plane of the roadway, while the light rays are projected from reflector 6 substantially parallel to the roadway above the same, and light rays from reflector 7 are projected down against the roadway, while those from reflector 8 are directed down against reflector 6.

It is believed the operation will be obvious and may be briefly stated as consistent of 55 utilization of the lower light for suburban service, while the upper light is employed 60

where detection of the roadway is not required.

Having thus described the invention, what I claim as new is:

1. A headlight structure comprising a reflector body consisting of a lower semi-paraboloidal section, a supplemental concave reflector arranged over said section and having its focal center coincident with the focal 70 center of the first mentioned reflector whereby the light rays from the concave reflector are reflected back through the focal center aforesaid, a source of light in said reflector, and means for deflecting upwardly directed 75 rays downwardly across the axis of the paraboloid.

2. A headlight structure comprising a reflector consisting of a main semi-paraboloidal reflector, a source of light arranged at 80 the focal center of said reflector, and a supplemental reflector of relatively small area co-operating with the main reflector and arranged in close proximity to the source of light and above the same, whereby to intercept the upwardly directed light rays close to the point of divergence of the same and reflect them back through the focal center of 85 and onto the main reflector.

3. A headlight structure comprising a 90 main semi-paraboloidal reflector, a source of light disposed substantially at the focal center of said reflector, a supplemental concave reflector of relatively small area extending forwardly of the apex and over the main reflector and having its focal center coincident with the focal center of said main reflector, and a flat reflector above the axis of the paraboloid and joining the front edge of the supplemental reflector and extending to the 95 base of the main reflector to intercept the upwardly directed rays emanating from the portion of the source of light not at the focal center aforesaid.

4. In a headlight structure, the combination, with a casing, of a reflector in the lower portion thereof comprising substantially the lower half of a paraboloidal reflector and a cover for said lower half having its forward portion flattened to provide a maximum 100 space intermediate the cover and the top portion of the casing, and an independent reflector in said casing disposed in the upper portion thereof and occupying the space unoccupied by the first mentioned reflector, 105 said independent reflector having its upper portion conforming to the casing and its lower portion conforming to the flattened portion of the cover aforesaid and seating thereon.

In testimony whereof I affix my signature.

EUGENE F. MEADOR.
